Primary Examiner — Cathron C Brooks*Assistant Examiner* — Sharon S Oum(74) *Attorney, Agent, or Firm* — Seed Intellectual Property Law Group LLP(57) **CLAIM**

The ornamental design for a trim ring for ventilation housing, as shown and described.

DESCRIPTION

FIG. 1 is an axonometric top, front, left view of my new design.

FIG. 2 is an axonometric bottom, rear, left view of my new design.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines illustrate portions of the trim ring for ventilation housing that form no part of the claimed design.

1 Claim, 6 Drawing Sheets(56)
